HASSOCK

Philip K. Madan, Mount Vernon, N. Y.

Application January 7, 1946, Serial No. 639,591

2 Claims. (Cl. 155—169)

1

This invention relates to hassocks. More particularly, the invention deals with articles of manufacture of this kind composed, for the major part, of paperboard and paper facings in the production of an economical article of this kind. Still more particularly, the invention deals with means for reinforcing and strengthening the upper open end portion of the body of the hassock to maintain the same against crushing or spreading strains in the use of the device and, also, in providing a relatively large upper surface upon the cushioned cover of the hassock which is disposed in the body portion of the hassock, being in the form of a box-shaped container.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of a hassock made according to my invention.

Fig. 2 is a side view with parts of the construction broken away and in section; and

Fig. 3 is a diagrammatic plan view of a cardboard or paperboard sheet, from which two elements or parts of the hassock are formed.

In the construction shown, the hassock comprises a box-shaped part 10 and a cover part 11, both more or less octagon in horizontal section, that is to say, considering the box 10, this box has opposed relatively wide front and rear walls 12; somewhat narrow side walls 13 and still narrower corner walls 14, so as to produce a more or less oblong construction. The contour of the cover 11 conforms with that of the box 10. The box 10 is composed of a single cardboard or paperboard sheet folded to form the various walls 12, 13 and 14 and these walls are covered by an inner facing 15 and outer facing 16, note the right side of Fig. 2. The bottom wall 17 is fitted snugly within the walls and upon the inner facing 15 with the outer facing having an inturned flange 18 glued or otherwise secured to the lower surface of the bottom wall 17. The bottom wall 17 fits snugly upon the walls 12, 13 and 14 and conforms to the contour thereof.

Fitted into the inner surfaces of the walls 12, 13 and 14, at the upper edge thereof and upon the facing 15, is an octagon ring 19, note Fig. 3. This ring is cut from a cardboard or paperboard and of a contour to fit snugly within the walls 12, 13 and 14 to brace said walls at the upper edge thereof. The outer facing 16 has a flange 55

portion 20, which extends inwardly to completely enclose the ring 19 and to extend onto and be secured to the facing 15, as seen at 21, note the upper right-hand corner of the box 10, as seen in Fig. 2.

In the more economical construction of the hassock, the facings 15 and 16 will be composed of suitably colored and characterized papers. However, in more expensive hassocks, the facing 16 may be composed of leatherette or leather or a sheeting of any desired material and, in still more expensive hassocks, the facing 15 may also be of leather. This also applies to the facing materials of the cover 11, it being preferred that the upper facing sheet 22 of the cover be provided of leatherette or leather to compensate for the flexure thereof upon the soft packing of any suitable material 23. This also applies to the peripheral facing 24 which joins the facing 22 in a beaded finished edging string 25. The base of the cover is provided with a suitable stiff bottom 26, to which the inturned edge of the annular facing 24 is secured. Secured to the bottom 26 is a supplemental bottom 27, which may also be faced, as seen at 28, the bottom 27 being formed of that part of the cardboard or paperboard sheet cut from within the ring 19, note Fig. 3. In this manner, no real waste is experienced, except in trimming the edges and in allowing sufficient clearance, as at 29, between the parts 19 and 27 to compensate for the facings 28, 16, and still provide slight clearance, as at 30 to fit the supplemental bottom 27 within the upper portion of the hassock box 10. This supplemental bottom retains the cover 11 against lateral displacement from the box or container, as will be apparent.

The thicknesses are exaggerated in Fig. 2 for sake of clarity, it being understood that thin sheetings are used on the respective facings and, in fact, the thicknesses of the parts 19 and 27, as well as 26, may be modified. It will appear that the cover 11 is of an outside diameter corresponding to the diameter of the box or container 10, so that the lower portion of the cover outwardly of the supplemental bottom 27 seats upon the upper reinforced edge of the box, as seen at 31, at the left of Fig. 2 of the drawing, the load being taken directly upon the vertical walls 12, 13 and 14 of the box or container member of the hassock.

With my construction, I provide a hassock having a soft, comfortable seat or support at the top thereof, at the same time, providing a container in which various kinds and types of articles can be placed for storage. This is particularly

desirable in a child's room where toys and similar articles can be stored; whereas in a living room, books, magazines and other articles can be stored in the compartment of the box or container.

It will be apparent that the upper surface of the ring 19 is flush with the upper edges of the walls of the box part in providing the flat surface upon which the cover seats, as at 31. Descriptively speaking, the box part may be said to comprise a tube having a bottom wall closing one end of the tube and a continuous ring reinforcing and supporting the other upper end of said tube.

Having fully described my invention, what I claim as new and desire to secure by Letters Patent is:

1. A hassock of the class described comprising a tubular body having angularly disposed walls formed from a single piece of paper-board, a bottom wall having outer peripheral edges conforming with and snugly arranged within said body walls and closing one end of the tubular body, the other upper end of said body having a circumferentially continuous flat paper-board ring of a shape conforming with and fitting snugly within the walls of said body to support and reinforce the upper end of said body walls, the upper surface of said ring being flush with the upper edge of the tubular body, a facing for the entire outer surface of the body walls, the upper end portion of said facing extending around said ring onto the inner surface of said walls in supporting said ring on said body, a cover for closing the upper end of said body, and an extension on the lower surface of the cover having peripheral edges conforming with and fitting closely in said ring in retaining the cover against accidental displacement from the upper end of said body.

2. A hassock of the class described comprising a tubular body having angularly disposed walls formed from a single piece of paper-board, a bottom wall having outer peripheral edges con-

forming with and snugly arranged within said body walls and closing one end of the tubular body, the other upper end of said body having a circumferentially continuous flat paper-board ring of a shape conforming with and fitting snugly within the walls of said body to support and reinforce the upper end of said body walls, a facing for the entire outer surface of the body walls, the upper end portion of said facing extending around said ring onto the inner surface of said walls in supporting said ring on said body, a cover for closing the upper end of said body, an extension on the lower surface of the cover having peripheral edges conforming with and fitting closely in said ring in retaining the cover against accidental displacement from the upper end of said body, the upper surface of said ring and the lower surface of the bottom wall being flush with upper and lower edges of the body walls, and the outer facing of said body walls extending onto the lower surface of said bottom wall.

PHILIP K. MADAN.
